UNITED STATES PATENT OFFICE.

THOMAS F. CAMPBELL, OF DENVER, COLORADO, ASSIGNOR OF SIXTY ONE-HUNDREDTHS
TO RICHARD S. SHANNON, OF DENVER, COLORADO.

DERRICK.

Application filed June 28, 1926. Serial No. 119,005.

My invention relates to derrick structures of the type used in drilling and operating oil, gas and artesian wells and its primary object is to provide a structure composed of two tower-units of dissimilar lengths one of which is removably mounted with relation to the other.

Another object is to provide by means of the two tower units, two crown blocks, placed one above the other and having pulleys relatively disposed to cooperate in the work of drilling the well. Another object of the invention resides in the provision of a simple and highly efficient method of connecting the tower units so that they reenforce one another and so that the removable unit is readily dismantled and removed without disturbing the other, relatively stationary unit.

A further object of the invention resides in the construction of the crown blocks and of the means for mounting the pulleys upon the same whereby the latter are readily moved relative to each other or changed in number by simple adjustments of the parts which hold them in their operative position on the respective tower-units.

Still another object resides in providing means for taking up wear on the shafts on which the pulleys are supported, and further objects are to be found in novel arrangements of parts and details of construction all of which contribute to the provision of a derrick structure in which simplicity of construction is combined with strength and durability and with more than ordinary efficiency and practicability in operation, as will fully appear in the course of the following description.

In the accompanying drawings in which like characters of reference designate corresponding parts throughout the several views,

Figure 1 represents an elevation of a tower constructed in accordance with my invention,

Figure 2 an enlarged horizontal section taken on the line 2—2 Figure 1,

Figure 3, an enlarged fragmentary view of adjoining legs of the two tower units of the structure showing the method of their connections by clamp-elements of novel construction,

Figure 4, an enlarged horizontal section of the legs above one of the clamps,

Figure 5, a section along the line 5—5, Figure 4,

Figure 6, a section similar to that of Figure 4, showing the clamp element in the condition after the removable tower unit has been detached from the permanent unit,

Figure 7, an elevation of the two crown-blocks of the derrick structure at the upper ends of the two tower-units comprised therein, drawn to an enlarged scale and showing the relative arrangement of the pulleys on the blocks,

Figure 8, an elevation of the crown blocks, looking in the direction of the arrow A in Figure 7,

Figure 9, a horizontal section in the plane indicated by the line 9—9 in Figure 7,

Figure 10, an enlarged section on the line 10—10 Figure 9,

Figure 11, a sectional detail of the upper end of one of the legs of the removable tower unit, showing the method of supporting the crown block thereon,

Figure 12, an enlarged section on the line 12—12, Figure 1, showing the construction of the clamps employed for fastening together the sections of which the legs of the removable tower-unit are composed, and

Figure 13, a perspective view of the upper portion of the tower.

Referring further to the drawings the permanent tower-unit of the derrick structure is composed of four slightly converging legs 5 of tubular formation which are supported by base plates 6 on a suitable foundation structure. The legs are fastened together by girders 7 and braces 8, and they support at their upper extremities a crown block composed of I-beam sills 9, and cross beams 10 of similar form on which the pulleys used in drilling the well, are mounted.

The legs of the unit are each composed of end-to-end abutting sections which are connected together by clamp-elements herein-after to be more fully described.

The removable tower unit which is lower than the permanent unit is supported upon the foundation, within the latter and it is composed of four legs 12 which extend parallel to and in spaced relation to the legs of the outer unit. The legs of the inner unit are each composed of end-to-end abutting sections connected by sleeve-clamps 13 shown in detail in Figure 12, and they support at their upper ends a crownblock which like the first described block, is composed of I-beam sills

14 and cross-beams 15 of similar form, upon which are mounted a number of pulleys as will hereinafter be more fully described.

The clamp-elements which connect the sections of the legs of the outer, permanent unit of the derrick structure, also function to fasten the legs of the inner removably unit and they are, with this end in view, composed of flanged saddle-members 16 fitted upon the 10 legs of the outer unit across the joints between the sections thereof and fastened to one of the sections by bolts 17, blocks 18 fitted in the spaces between the corresponding legs of the two units, clamp-plates 19 15 engaging the legs of the inner units opposite to the saddles, U-bolts 20 which embrace the saddles and pass through openings in the clamp-plates, and nuts 21 screwed upon the ends of the bolts in engagement with the 20 plates 19.

The braces and girths of the permanent tower-unit are flattened at their extremities, and the flattened portions are inserted in the spaces between the spacing-blocks 18 of the 25 clamp-elements and the flanges 22 of the corresponding saddle members 16 of the same.

Machine bolts 23 in alined holes of the flanges, the ends of the braces and the blocks secure these parts in rigid connection with 30 each other.

It will thus be observed that the clamp-elements perform the three-fold function of connecting the leg-sections of the outer tower-unit, of fastening the legs of the inner tower-unit, and of securing the braces and 35 girths of the permanent structure.

The sill-members 14 of the crown block on the inner, lower tower-unit are supported on caps 24 inserted in the ends of the tubular 40 legs of the unit. The sills 14 which extend in alinement with the pairs of slanting legs on which they are supported, converge accordingly and they support the horizontal cross beams 15 of the crown block upon which the 45 pulleys are mounted.

In order to provide a rigid support for the horizontal cross beams, wedge-shaped plates 25 are fastened upon the slanting sill beams as best shown in Figures 7 and 11. The 50 beams 14 and 15 are rigidly fastened by machine bolts 26, and the rigidity of the structure is further increased by the rods 27 which connect the sill beams at opposite ends thereof.

55 The legs 5 of the permanent tower unit, projecting beyond the crown block on the removable unit, are fastened to the beams 14 of said crown block by clamp-saddles 28 and their upper ends are provided with caps 29 60 similar to those shown in Figure 11, for the support of the sill-beams 9 of the upper crown-block.

The construction of the upper crown block is similar to that of the lower crown block 65 hereinbefore described, the cross beams 10 be-

ing fastened upon the beams 9 by bolts 30 and the spaces between the upper and lower beams being occupied by wedge-shaped fillers 31. The upper crown block supports two grooved pulleys 32 and 33 mounted for 70 rotation on shafts 34. The shafts are fastened on the cross beams 10 by horse-shoe clamps 35 which engage below the upper flanges of the beams 10.

The ends of the shafts have sockets or cavities 36 at quadrant points and the clamps 35 are provided with bolts 37 adapted to enter the cavities which are innermost.

The pulleys are mounted to rotate on their respective shafts between collars 38 which separate them from the beams 10 and which are held against rotation by shoulders 39 which engage the upper flanges of the beams. The position of the pulleys on the shafts may be varied by the use of collars of different widths and when the shafts become worn at their upper surfaces, the wear is readily taken up by partial rotation of the shafts and the adjustment of the bolts of the horse-shoe clamps from one of the cavities of 90 the shaft to another.

The two cross beams of the upper crown block are separated by spreaders 40 and they are rigidly fastened together by bolts 41 extending through alined holes adjacent their 95 ends.

The lower crown block of the inner removable tower-unit has a plurality of cross beams 15 supported on the two sill-beams 14. The outer cross beams are fastened upon the 100 beams 14 by bolts 26 and the other cross beams placed between the outer beams, are mounted for adjustment to different distances apart.

The various cross beams are separated from each other by spreaders 43 in the form of 105 angle plates, which are pivoted between the flanges of the beams as at 44, and engage with the webs of the next adjoining beams. Bolts 45 passing through alined apertures of the beams at opposite ends thereof, cooperate 110 with the spreaders to hold the beams in their adjusted positions.

It will be apparent that by the use of spreaders of different length, the cross beams may be placed apart at any desired distance, 115 it being understood that after the bolts have been loosened and the spreaders have been turned about their pivots or removed, the beams 15 between the outer beams which are bolted to the sill beams, may be slid along the 120 bolts in either direction.

Two shafts 46 are mounted on the cross beams by horseshoe clamps 47 engaging the flanges of the outer beams 15 as in the upper crown block hereinbefore described, and the shafts are also adjustable by partial rotation to take up wear. Each shaft supports a plurality of grooved pulleys 48 placed in the spaces between the cross-beams, and the pulleys are spaced from the beams by collars 49 125

provided with shoulders 50 which by engagement with the beams, hold them against rotation.

It will be readily apparent that by the use of 5 collars and spreaders of different widths and by adjustment of the cross beams, the pulleys may be adjusted on the shafts to different distances apart and that their number can be increased or decreased as may be desired to adapt the derrick for different purposes and for use under varying conditions.

In operation, the pulleys on the two crown blocks cooperate in drilling a well centrally of the derrick structure. The pulley 32 of the 15 upper crown-block is the spudding pulley that supports the cable of the drilling tool and the other pulley 33 is the sand pulley that supports the cable used in bailing the excavation.

20 One of the pulleys on the lower crown block guides the cable of the spudding pulley to alignment with the center of the well in the axis of the derrick-structure and the other pulleys serve for the support of cables used 25 in the movement of casing-sections and machine parts employed in the formation of the well.

By the cooperative arrangement of the pulleys on the two crown blocks as hereinabove 30 described, a tower of the desired height can be erected without the extreme width or breadth of top required in tower structures in which all the pulleys are assembled on one and the same crown block.

35 The two frames reenforce one another and conjointly provide a structure of exceptional strength and durability and when the drilling operation is completed and the derrick is employed for pumping only, the inner tower 40 unit is readily removed from the outer permanent unit, for use at another location. The removal of the inner tower is easily accomplished by unfastening the clamps which connect the sill beams 14 to the legs 5 of the permanent 45 structure, dismantling the crown-block of which the beams are a part, and then removing the legs 12 in sections by detaching the U-bolts 20 from the clamps which secure the sections of the legs 5 of the permanent 50 structure.

The saddle-members 16 and the block 18 of the clamp-elements are not disturbed but remain in place as shown in Figure 6 to hold the sections of the legs of the permanent structure in alignment and to secure the girths and braces by which the legs are connected.

It is to be observed that the clamps as applied to the permanent structure are free from nuts which are liable to loosen by vibration.

60 While I do not desire to be limited to any size or shape of the material used in constructing the derrick, I prefer to make the inner removable tower unit of larger tubular metal than the outer unit, it having been found that 65 for standard work, the proportions of three

inches in diameter for the outer frame and four inches for the inner frame, will give the desired strength and stability. Different proportions may however be used according to the height of the structure and the nature of 70 the work on which it is to be employed and other variations relating to details of construction and the arrangement of parts may be resorted to within the spirit of the invention as defined in the hereunto appended 75 claims.

It is a distinctive feature of the invention that by the provision of a guiding pulley on the lower crown block the cable of the drilling tool is suspended to extend vertically in 80 the axis of the derrick to produce the well-bore in the center of the derrick floor without strain or undue friction.

What I claim and desire to secure by Letters Patent is:—

85 1. A derrick comprising a permanent tower unit, and an auxiliary tower unit, placed one within the other and each including a crown block and supporting legs, clamps connecting the legs of the auxiliary units to the legs of 90 the permanent unit, and clamps connecting the crown block of the auxiliary unit to the legs of the permanent unit.

2. A derrick comprising permanent and auxiliary tower units placed one within the 95 other, each having supporting legs, a crown block on each unit cooperating for the support of a cable in the operation of the well, and clamps connecting the crown block of one unit with the supporting legs of the 100 other unit.

3. In a derrick structure having auxiliary and permanent units, each having legs, the legs of the permanent unit being composed of end-to-end abutting sections and spaced from 105 the legs of the auxiliary unit, a clamping means comprising two connected parts adapted to conjointly embrace adjoining leg sections of the permanent unit, one of said parts being adapted to engage the corresponding leg of the auxiliary unit in the space between the legs, a clamp member disposed to engage the opposite side of the leg of the auxiliary unit, and a U-bolt embracing said parts, in detachable connection with the clamp member. 110

4. In a derrick structure having auxiliary and permanent tower units, one within the other, the permanent unit of which has legs composed of end-to-end abutting sections, 120 and braces between the legs, the auxiliary unit of which also has legs, a derrick clamp comprising two parts adapted to embrace adjoining leg sections of the permanent unit and spaced from each other to admit the braces of 125 the unit, bolts connecting the parts and for holding the braces, and a detachable member cooperating with one of the parts to clampingly secure a corresponding leg of the auxiliary unit.

5. In a derrick, a permanent tower unit having legs composed of end-to-end abutting sections and braces between the legs, an auxiliary unit having legs spaced from those of the permanent unit, a derrick clamp comprising two parts adapted to embrace adjoining leg sections of the permanent unit and spaced from each other to admit braces of the same, one of said parts being adapted to engage the corresponding leg of the auxiliary unit in the space between the legs, bolts connecting the parts to hold the braces, a clamp member adapted to engage the leg of the auxiliary unit, and a U-bolt embracing the parts, in detachable connection with the clamp member.
6. In testimony whereof I have affixed my signature.

THOMAS F. CAMPBELL.
